The ornamental design for a toothbrush with baseball bat handle, as shown and described.

DESCRIPTION

FIG. 1 is a front elevational view of my design showing my toothbrush with baseball bat handle;

FIG. 2 is a right side elevational view of my design, the left side elevational view being the mirror opposite thereto;

FIG. 3 is a top plan view thereof;

FIG. 4 is a bottom plan view thereof; and,

FIG. 5 is a rear elevational view thereof.
